UNITED STATES PATENT OFFICE.

GAETANO PAGANO, OF BROOKLYN, NEW YORK.

APPAREL SHELTER.

Application filed July 6, 1925. Serial No. 41,892.

This invention relates to improvements in apparel shelters, and has for its object to provide a dust-proof apparel containing bag.

5 Another object of the invention is to provide a clothes rack with a flexible dust-proof covering.

A still further object of the invention is to provide a collapsible clothes closet formed 10 of cloth.

With the above and such other objects as may hereinafter more fully appear, I have invented the device illustrated in the accompanying drawings, in which:

15 Figure 1 is a front elevational view of my device.

Figure 2 is a similar view thrown open to expose the contents thereof.

Figure 3 is a side view.

20 Figure 4 is a top plan view.

Figure 5 is a transverse sectional view adjacent the lower edge of the device.

Figure 6 is a top plan view of a supporting rack.

25 Figure 7 is a perspective view of the device rolled for transportation purposes.

Like reference characters indicate like parts throughout the following specification and in the several views in the drawings, in 30 which 1 indicates a dust-proof apparel container embracing a bag 2 formed of a back portion 3 to which is stitched a top horizontal panel 4, and to the front edge of the latter is stitched a drop curtain 5. Stitched 35 to the edges of the member 3 are side panels 6 and 7. To the bottom edge of the member 3 is stitched a panel 8, all of said panels being of the same width. To the front edge of the panel 8 is stitched a shield 9 which 40 extends up to substantially the central portion of the device and is secured in its raised position by means of tie string members 10 and 11, 12 and 13, secured respectively to the upper corners of the member 9 and to the 45 members 6 and 7. Stitched to the forward edges of the panels 6 and 7 are front panels 14 and 15, the free edges of which are adapted to overlap each other and be held in overlapping or closed position by means of tie 50 strings 16 and 17, the lower portions of said panels 15 and 16 being adapted to seat within the member 9. The upper corner 18 of the member 14 is slidably secured to the rail 19 of a supporting frame 20 by means of a tie string 21. The upper corner 22 of the member 15 is adapted to be secured to the

rail 19 by means of a tie string 23. Secured to the corners 24 and 25 of the curtain 5 are tie strings 26 adapted to be secured to the tie strings 27 on the members 60 14 and 15, whereby said member 5 will be held in closed position overlapping the upper parts of said members 14 and 15.

The frame 20 is a rectangular member 65 formed from a strand of heavy wire, being doubled upon itself along the side 28 and having a loop 29 projecting upwardly from its central portion and extending through a slot 30 in the said top panel 4, whereby the complete device may be suspended from a hook, nail or any other suitable place. Certain parts 31 and 32 of the wire forming the member 20 extend forwardly and are formed 70 into co-acting spring rings 33 and 34 adapted to be pressed apart from one another in order to receive the ends 35 and 36 of the hanger rod 37, upon which a coat hanger 38 or other suitable suspending means for wearing apparel may be hung. The extreme 75 terminals 39 and 40 of the wire forming the member 20 are projected from the rear side 28 thereof to form hooks for hats or other articles to be enclosed in the bag.

In many cases, especially in cases of tourists, travelers or those finding it necessary 80 to live in hotel or boarding house rooms or in camps where clothes cupboards are not accessible, it has been found very difficult to provide means for keeping wearing apparel 85 out of the dust. Therefore I have provided the above described dust-proof apparel containing bag so formed that it may be rolled into a compact bundle to be carried in a trunk or otherwise in moving about from place to place and may be quickly hung up 90 to form a dust-proof shelter for apparel.

Having described my invention, that 95 which I claim as new and desire to procure by Letters Patent is:

1. An apparel bag comprising a box like 100 structure including a top having a slot centrally arranged therein, a back, sides and bottom and a front formed of overlapping panels, a frame formed from a strand of wire bent intermediate its ends to form a 105 loop passing through the slot and adapted for supporting the bag from a supporting means, forwardly extending portions forming the ends of the frame being bent at right angles, said wire having its ends terminating 110 in spaced parallel arranged hooks, a rod having its ends received in the forward ex-

tending portions, and tie strings secured to the panels of the front and being associated with each other and the frame respectively for securing the panels in their overlapping 5 relation.

2. An apparel bag comprising a box like structure including a top having a slot centrally arranged therein, a front formed of overlapping panels, tie strings secured to 10 said panels for securing them in their overlapped position, a frame formed from a strand of wire bent to provide a loop vertically extending through said slot for supporting said bag, forwardly extending end 15 portions for said frame and being arranged into coacting spring rings, said wire having its ends terminating between the ends of the frame and arranged to provide spaced hooks and a hanger rod received in said spring 20 rings.

3. An apparel bag comprising a box like structure including a top having a slot centrally arranged therein, a front formed of overlapping panels, tie strings secured to said panels for securing them in operative 25 association, a frame formed from a twisted strand of wire bent intermediate its ends to provide a loop vertically extending through said slot and being adapted to receive a supporting means for said bag, forwardly extending end portions for said frame and being arranged in parallelism, a hanger rod adapted to be supported by the forwardly extending end portions, and said wire having its ends terminating between the forwardly extending end portions and shaped 30 to provide hooks.

In testimony whereof I affix my signature.

GAETANO PAGANO.
